UNITED STATES PATENT OFFICE

2,314,370

MARINE PROPULSION

August Rietzke, Gordons Corners, N. J., assignor,
by mesne assignments, to Bow Arch Corporation,
Mercer County, N. J., a corporation of
New Jersey

Application January 16, 1941, Serial No. 374,759

3 Claims. (Cl. 115—37)

This invention relates to marine propulsion and it is primarily an object of the invention to provide a means of propulsion of this kind embodying the use of twin propellers, and wherein said propellers are so positioned and mounted with respect to the rudder of the boat to assure the boat to continue to travel straight ahead in the event either of the propellers should become ineffective.

Another object of the invention is to provide a means of this kind wherein the propellers are positioned at predetermined points forward of and to opposite sides of the rudder post whereby the wash from each of the propellers is caused to strike the rudder blade at substantially the center thereof so that when one of the propellers should become ineffective, the boat will continue to travel straight ahead.

An additional object of the invention is to provide a marine propulsion wherein twin screws are employed and wherein the axes of rotation of the propellers are in convergence toward the center of frictional resistance on the surface of the hull of the ship, and also wherein each of the propellers is positioned ahead or in advance of the rudder post a distance equal to the distance between the axial center of both of the propellers, said centers of the propellers, of course, being aligned in a direction at right angles to the center line of the boat, and wherein said propellers each has its axial center positioned to one side of the center line of the hull a distance equal to one-half of the distance from the center line of the hull to a point on the water line directly above the propeller.

In the drawing:

Fig. 1 is a diagrammatic view in top plan illustrating a marine propulsion assembled and arranged in accordance with an embodiment of my invention.

Fig. 2 is a diagrammatic view in side elevation having indicated thereon certain lines whereby is computed the location of a propeller.

Fig. 3 is a diagrammatic view taken substantially on the line 3—3 of Fig. 1.

Fig. 4 is a diagrammatic view taken of the stern.

Fig. 5 is an elevational view of a diagrammatic character of the rudder as herein comprised.

While the accompanying drawing particularly illustrates the invention in connection with a surface traveling boat and the following description is based thereon, it is to be understood that the same principles as herein embodied can be employed to the same advantage in connection with aircraft and under which circumstances the positioning of the propellers will be reverse to what is herein described and illustrated.

The present embodiment of the invention is based upon a boat structure wherein the center

line of the hull H at the water line is 50 feet and the distance over the outside surface of the hull from the keel line to the water line at the greatest breadth of the hull H is 7 feet. It is to be stated at this time that in referring to lengths, the full length is given, but in referring to a breadth, only a half width is given, which is in accordance with the agreed rules of naval architects.

10 The propellers P rotate upon axes which forwardly converge toward the center line of the hull at the point CR or frictional resistance of the water upon the submerged surface of the hull when the boat is traveling at a predetermined rate of speed. These propellers P are also so positioned at opposite sides of the center line of the boat and at such points forwardly of the rudder post to assure the inner portion of the wash from each of the propellers, as indicated at 2, to strike the adjacent surface of the rudder blade B at substantially the center thereof. This striking of the wash upon each surface of the rudder blade B is to occur when said blade B is in straight ahead position or within a variation of not over 10°.

25 The propellers P are positioned forwardly from the rudder post a distance substantially equal to the distance between the axes of rotation of the propellers and each of said propellers has 30 its axes of rotation to one side of the center line of the boat a distance equal to substantially one-half of the distance between the center line of the boat and the water line directly above the propeller. This particular location of each of 35 the propellers P with respect to the blade B, and the diversion of the axes of the propellers with respect to the center line (CLOB) of the hull constitutes the essential feature of the present invention as by this particular assembly, the 40 boat will be caused to continue to travel straight ahead in the event either of the propellers P should become ineffective due to the fact that the action of the wash from the working propeller upon the central portion of the rudder blade B will resist the tendency of the hull H to swing under the action of the one operating propeller.

45 By "wash" is meant the water between the slip stream and the hull and which water or "wash" moves at a greater speed.

In the accompanying drawing, the following lines denote the following:

50 AB=distance over the outside surface of the hull from water line to keel line at the bow.

55 BC=distance over the outside surface of the hull from keel line to water line at greatest breadth of the submerged hull.

PL1F=Fig. 2, distance over the outside surface of the hull from forward stem or bow at water line to greatest breadth of hull at water line.

FE=distance over the outside surface of the hull from keel to water line at the stern of the boat.

PLA, Fig. 2=distance over the outside surface of the hull at the water line from the greatest breadth of hull to stern of boat at water line.

To establish the center of resistance I , the distance AB and the distance BC, as indicated in Fig. 3, are added and the resultant sum is divided by 2. The quotient obtained is multiplied by the distance PLA, Fig. 2. Then there is added the distance BC, Fig. 3, and the distance FE, Fig. 4. This total is divided by 2 and the quotient multiplied by the distance PLA, Fig. 2. The first product is subtracted from the second product and this remainder is divided by 2 and the quotient divided by the distance CB, Fig. 3, the product of which is added to distance PLA, Fig. 1, which will be the center of resistance CR, Fig. 1, in feet from the bow of the boat along the keel line.

Assuming the distance (AB) over the outside surface of the hull from water line to keel line at the bow is 2 feet and the distance (BC) over the outside surface of the hull from keel line to water line at greatest breadth of the submerged hull is 7 feet, the total of AB and BC will be 9 feet. Dividing this 9 feet by 2 gives 4.5 feet. Presuming the distance (PLA) over the outside surface of the hull from forward stem or bow at water line to greatest breadth of hull at water line is 21 feet, this dimension PLA is multiplied by 4.5 which gives 94.5 sq. ft. Presuming the distance (FE) over the outside surface of the hull from keel to water line at the stern of the boat is 5 ft., this dimension is added to the 7 ft. (BC), Fig. 3. The resultant sum of 12 is divided by 2, giving 6 ft. This 6 ft. is multiplied by 28, the distance (PLA) Fig. 2, over the outside surface of the hull at the water line from the greatest breadth of hull to stern of boat at water line, giving 168 sq. ft. The 94.5 sq. ft. hereinbefore noted is subtracted from the 168 sq. ft., giving a remainder of 73.5 sq. ft. This 73.5 is divided by 2, giving a result of 36.75. This 36.75 is divided by 7 (BC) Fig. 3, which as hereinbefore stated, is the distance over the outside surface of the hull from keel line to water line at greatest breadth of the submerged hull. This gives a quotient of 5.25 ft., which is to be added to 21 ft., which is the distance (PLA) Fig. 1, from forward stem or bow at water line to greatest breadth of hull at water line. The total 26.25 is the distance of the center of frictional resistance (CR) from the bow at the center line of boat (CLOB).

The additional lines denote the following:

BW=the point of the water line at the bow.

SW=the point of the water line at the stern.

AC=greatest breadth in feet of boat at water line.

COR=center of rudder post.

CR=center of resistance.

COS=the point which controls the determination of the angle of the axis of the propeller.

CLOB=the center line of boat.

WL=water line.

To determine the position of shaft, the length of boat in feet at water line between BW and SW, which has hereinbefore been stated as 50 feet, is divided by 6 which is the presumed distance AC, which is the greatest breadth in feet of boat at water line, which is 8.33 feet. There is then laid off a line 8.33 inches from the center line of the boat at the keel line at the center of the rudder post (COR) and at right angles to

said center line of the boat. The outer end of this line constitutes a point COS which is the point which controls the determination of the angle of the axis of the propeller. It is to be particularly noted that the length of this line in inches is of a number equal to the number of feet resulting by the dividing by 6 the distance between BW and SW which, as hereinbefore stated, is the length of the boat at the water line. The axis of rotation of a propeller P is in parallelism with an imaginary line at the point COS to the center of resistance CR. The true position of the propeller is half the distance on a line between the imaginary line connecting the point CR and COS and the water line between BW and SW and forwardly of the center of the rudder COR a distance equal to the full length of the line from COS to the water line (WL) and at right angles to the center line of boat (CLOB).

The rudder area is 1 square inch to 1 square foot of submerged surface of hull and the area of the balance of the rudder should be $\frac{1}{3}$ of the area of the rudder blade. The depth of the rudder should be calculated with respect to the draft of the boat amidship.

The foregoing calculations are based on boats of 1 h. p. to 2 square feet of submerged resistance up to 75 feet in length and are effective in a leeway of $12\frac{1}{2}\%$ above or below. For each 30% power increase to the square foot of submerged surface of hull and increase of length of hull, the degree of angle of the axes of the propellers with respect to the center line (CLOB) of the hull should be advanced 1°.

What is claimed is:

1. The combination with a hull of a boat and a rudder at one end portion thereof; of propellers at opposite sides of the center line of the boat ahead of the rudder, the axes of the propellers converging toward the bow, said axes being outwardly of and in parallelism with imaginary lines from the center of frictional resistance on the surface of the hull to points aligned in a direction at right angles to the center line of the hull at the rudder post, each point being spaced from said center line of the hull at the rudder post in inches a distance determined by the quotient resulting from dividing the distance in feet over the outside surface of the hull at the water line from the bow to the stern of the hull by one-half of the greatest breadth in feet of the hull at the water line, the axial centers of the propellers being aligned in a direction at right angles to the center line of the hull, each propeller being positioned such a distance to one side of the center line of the boat as to cause the wash of the propeller to strike the blade of the rudder.

2. The combination with a hull of a boat and a rudder at one end portion thereof; of propellers at opposite sides of the center line of the boat ahead of the rudder, the axes of the propellers converging toward the bow, said axes being outwardly of and in parallelism with imaginary lines from the center of frictional resistance on the surface of the hull to points aligned in a direction at right angles to the center line of the hull at the rudder post, each point being spaced from said center line of the hull at the rudder post in inches a distance determined by the quotient resulting from dividing the distance in feet over the outside surface of the hull at the water line from the bow to the stern of the hull by one-half of the greatest breadth in feet of the hull at the water line, the axial centers of the propellers being aligned in a direction at right angles to the center

line of the hull, each propeller being positioned such a distance to one side of the center line of the boat to cause the wash of the propeller to strike the blade of the rudder, the propellers being positioned forwardly from the rudder post a distance substantially equal to the distance between the axes of the propellers, and each of said propellers having its axis to one side of the center line of the boat a distance equal to substantially one-half of the distance between the center line of the boat and the water line directly above the propeller.

3. The combination with a hull of a boat and a rudder at one end portion thereof; of propellers at opposite sides of the center line of the boat ahead of the rudder, the axes of the propellers converging toward the bow, said axes being outwardly of and in parallelism with imaginary lines from the center of frictional resistance on the surface of the hull to points aligned in a direction at right angles to the center line of the hull at the rudder post, each point being spaced from said center line of the hull at the rudder post in

inches a distance determined by the quotient resulting from dividing the distance in feet over the outside surface of the hull at the water line from the bow to the stern of the hull by one-half of the greatest breadth in feet of the hull at the water line, the axial centers of the propellers being alined in a direction at right angles to the center line of the hull, each propeller being positioned such a distance to one side of the center line of the boat to cause the wash of the propeller to strike the blade of the rudder, the propellers being positioned forwardly from the rudder post a distance substantially equal to the distance between the axes of the propellers, and each of said propellers having its axis to one side of the center line of the boat a distance equal to substantially one-half of the distance between the center line of the boat and the water line directly above the propeller, said axial centers of the propellers being alined in a direction at right angles to the center line of the boat.

AUGUST RIETZKE.
